US0D1106133S

(12) **United States Design Patent** (10) **Patent No.:** **US D1,106,133 S**
(45) **Date of Patent:** **** Dec. 16, 2025**

(54) **MOBILE PHONE**

(71) Applicant: **BEIJING XIAOMI MOBILE SOFTWARE CO., LTD.**, Beijing (CN)

(72) Inventor: **Zhen Wang**, Beijing (CN)

(73) Assignee: **BEIJING XIAOMI MOBILE SOFTWARE CO., LTD.**, Beijing (CN)

(**) Term: **15 Years**

(21) Appl. No.: **29/943,608**

(22) Filed: **May 22, 2024**

Related U.S. Application Data

(62) Division of application No. 35/516,553, filed on Feb. 24, 2023 (U.S. filing date under 35 U.S.C. 384), and having an international filing date of Feb. 24, 2023, now Pat. No. Des. 1,032,585.
